United States Patent Office.

THOMAS CUTTER, OF BIRMINGHAM, ASSIGNOR TO FRANK SEMPLE, H. C. FRY,
AND JOHN D. REYNOLDS, OF PITTSBURG, PENNSYLVANIA.

Design No. 3,154, dated August 11, 1868.

DESIGN FOR FEET AND STEMS OF GLASSWARE.

The Schedule referred to in these Letters Patent and making part of the same.

TO ALL WHOM IT MAY CONCERN:

Be it known that I, THOMAS CUTTER, of the borough of Birmingham, in the county of Allegheny, and State of Pennsylvania, have invented a new and useful Design for Footed and Stemmed Articles of Glassware; and I do hereby declare the following to be a full, clear, and exact description thereof, reference being had to the accompanying drawing, making a part of this specification, which is a perspective view of a glass goblet, and illustrative of my design.

My improved design for footed and stemmed articles of glassware consists in making such articles with a triple stem resting on an annular foot.

That the character of my invention may be readily understood, I will proceed to describe the same.

a is the bowl of a goblet; *b b* constitute a triple stem, each member of which extends from the bowl *a* above to the foot *c* beneath. This foot *c* has an annular opening, *d*, inside the points of union of foot *c* and stems *b*. The stems *b* may be curved toward each other, as shown, or have other regular or irregular curve, as may be preferred, or made straight.

This design I apply not only to goblets, but also to lamps, and other footed and stemmed articles of glassware.

What I claim as my invention, and desire to secure by Letters Patent, is—

The design for the feet and stems of articles of glassware, as hereinbefore set forth.

In testimony whereof, I, the said THOMAS CUTTER, have hereunto set my hand.

Witnesses:

JAMES SALISBURY,
CHARLES LEE.

THOS. CUTTER.
